UNITED STATES PATENT OFFICE.

AUSTIN F. JACKSON, OF TAUNTON, MASSACHUSETTS, ASSIGNOR TO THE REED & BARTON CORPORATION, OF SAME PLACE.

DESIGN FOR A SPOON, &c.

SPECIFICATION forming part of Design No. 20,811, dated June 2, 1891.

Application filed May 8, 1891. Serial No. 392,106. Term of patent 7 years.

To all whom it may concern:

Be it known that I, AUSTIN F. JACKSON, residing at Taunton, in the county of Bristol and State of Massachusetts, have invented and 5 produced a new and original Design for Handles of Spoons, Forks, and Similar Articles, of which the following is a specification, reference being had to the accompanying drawing, forming part thereof, and in which the figure 10 is a face view of a spoon the handle of which is designed according to my invention.

For this design I have devised and adopted figures and symbols commemorative and remembrance of the early history of the city of 15 Chicago, and the leading feature of such design consists in the representation of log cabins situated near a stream.

a indicates the cabins, and *b* the stream, which appear in connection with a suitable 20 background, the whole being surrounded by

an ornamental border *c*, and underneath such border is a transverse wreath-like ornament *d*, and below the ornament *d* are represented the word and numerals "Chicago, 1833," which word and numerals may be omitted, if desired, 25 as they form no part of the design. All of the above ornamentations appear on the handle of a spoon; but it is manifest that they may appear on the handles of forks, knives, ladles, and the like. 30

Having thus described my invention, what I claim, and desire to secure by Letters Patent, is—

The design for the handles of spoons, forks, knives, ladles, &c., as herein shown.

AUSTIN F. JACKSON.
